JOHN F. O'CONNOR, OF CHICAGO, ILLINOIS, ASSIGNOR TO WILLIAM H. MINER, OF CHICAGO, ILLINOIS.

DRAFT-YOKE FOR RAILWAY-CAR DRAFT-RIGGING.

1,128,353.

Specification of Letters Patent.

Patented Feb. 16, 1915.

Application filed February 21, 1913. Serial No. 749,906.

To all whom it may concern:

Be it known that I, JOHN F. O'CONNOR, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of 10 this specification.

My invention relates to improvements in draft yokes for railway car draft rigging.

The object of my invention is to provide 15 a draft yoke having a preliminary compression resisting member. I accomplish this object by providing the rear end of a U-shaped draft yoke with a spring cage adapted to receive a spring, and a spring 20 cap operating therein and in engagement with the spring or springs, and arranged to bear against the rear follower or a compression resisting member within the yoke so that in the movements of the yoke 25 through its connection with the draw bar a preliminary compression resisting movement may be afforded in connection with different types of draft gear, and may thus afford such movement in a draft rigging in 30 which the draft gear does not within itself contain any preliminary compression resisting members.

In the accompanying drawings forming 35 a part of this specification Figure 1 is a side elevation of a draft rigging embodying my invention. Fig. 2 is a plan view. Fig. 3 is a perspective view of the rear end of the draft yoke and the preliminary compression resisting member connected there- 40 with partly cut away to show the interior mechanism of said member.

In the drawings 4, 4 represent draft sills or parts of the car frame to which the draft rigging is attached, 5 a draw bar, 6 a tie- 45 plate, 7, 7 stop members provided with the front stop shoulders 8, 8, and rear stop shoulders 9, 9, 10 a U-shaped draft yoke suitably secured at its forward free ends to the draw bar 5 the connecting means illustrated 50 in the drawings being the pin 11 passing through the yoke and draw bar. Between the upper limb 12 and the lower limb 13 of the draft yoke are the front and rear fol- 55 lowers 14 and 15 respectively, the rear fol-

in the drawings being an integral member thereof, 16 represents the draft gear.

The inner rear end 17 of the draft yoke is provided with a spring cage 18 suitably secured therein, preferably by the outwardly 60 extended flanges 19, 19 which engage the sides of the yoke strap, the said spring cage being provided with a forwardly opening recess 20, preferably rectangular in shape, containing the springs 21, preferably 65 coiled springs, two in number, and one nested within the other, the said springs being seated at their rear ends against the rear portion 22 of the spring cage, and at their forward end within the hollow portion 23 70 of the spring cap 24. The spring cap 24 is preferably provided at either side with the faces 25, 25 adapted to slidably engage the sides of the recess 20 in the spring chamber, and is also provided with a forwardly opening recess 26 which receives the head 27 of 75 the bolt 28, the said bolt passing rearwardly through the rear end of the yoke, and being provided in the outer surface of the yoke with the nut 29.

Although I have described the member 28 as a bolt, yet it will be understood that the same might be a rivet or other connecting member headed at the ends and hence where I employ the term bolt throughout this 85 specification and in the claim, I wish it understood as covering all such devices.

The recess 26 is of sufficient length to permit the movement of the bolt head 27 in the reciprocating movements of the spring cap. 90 The said spring cap is provided with a rearwardly extending flange 30 adapted to guide the spring cap in its reciprocating movements, and prevent binding of the springs within the spring chamber upon lateral 95 movement of the yoke. The forward face 31 of the spring cap engages the follower 15, and in normal position of the parts of the draft rigging is extended forwardly from the front face 32 of the spring chamber. 100

Any suitable draft gear or compression resisting member may be inserted within the yoke. On forward movement of the yoke the springs 21, which in preferable construction are of lesser capacity than the compression resisting member 16, are compressed through the engagement of the spring cap against the follower 15, and upon full inward movement of the spring 110

cap the compression resisting member 16 continues its compression resisting action in the usual manner. On rearward movement of the draw bar the front follower 5 presses the compression resisting member 16 in the usual way.

It will be apparent that this device insures an easy preliminary movement in the draft rigging, and a consequent easy start 10 of the car to which the draft rigging is applied when employed with any type of draft gear suitable for insertion between the limbs 12 and 13 of the draft yoke 10.

I claim:—
15 In a railway draft rigging the combina-

tion with a compression resisting member of a draft yoke adapted to receive said member, the draft yoke being provided at its rear end with a spring cage, springs within the same, a spring cap engaging said 20 springs, a bolt slidably connecting the spring cap to the draft yoke, the spring cap being provided with a rearwardly extended flange adapted to telescope with the spring cage on relative movement of the spring cap 25 and draft yoke.

JOHN F. O'CONNOR.
